Edgar S. Stetthe

UNITED STATES PATENT OFFICE.

RICHARD MURRAY, OF NEW YORK, N. Y.

BUILDING BLOCK OR SLAB.

1,399,023.

Specification of Letters Patent.

Patented Dec. 6, 1921.

Application filed March 10, 1920. Serial No. 364,777.

To all whom it may concern:

Be it known that I, RICHARD MURRAY, a citizen of the United States, and residing at New York, in the county of New York and State of New York, have invented certain new and useful Improvements in Building Blocks or Slabs, of which the following is a specification, such as will enable those skilled in the art to which it appertains to make and use the same.

This invention relates to blocks or slabs preferably composed of cement, concrete or similar material and which are adapted to be used in the construction of the walls of buildings and roofs of buildings, and the object of the invention is to provide a block or slab of the class and for the purpose specified which is provided with one or more hook-shaped spring attaching devices by means of which the block or slab may be connected with and suspended from a suitable support; a further object being to provide means for reinforcing the block or slab; and with these and other objects in view the invention consists in a building block or slab which is simple in construction and efficient in use and which is constructed as herein-after described and claimed.

The invention is fully disclosed in the following specification, of which the accompanying drawing forms a part, in which the separate parts of my improvement are designated by suitable reference characters in each of the views, and in which:-

Figure 1 is an outside view of a part of the wall of a building which involves my improved blocks or slabs, part of the construction being broken away and in section;

Fig. 2 a partial transverse section on the line 2—2 of Fig. 1;

Fig. 3 a side and sectional view of one of my improved blocks or slabs which is used in the construction of the wall as shown in Figs. 1 and 2;

Fig. 4 a view similar to Fig. 3 of a modified form of the block or slab;

Fig. 5 a diagrammatic transverse sectional view of a part of a roof showing the same constructed with the blocks or slabs shown in Fig. 4; and,

Fig. 6 a side edge view of two different forms of blocks or slabs which I may employ in the construction of a building.

In Figs. 1 and 2, I have indicated for illustrative purposes, a part of the foundation 10 of a building, at 11 the upright

frame members and, in the practice of my invention, I secure to the members 11 a plurality of longitudinal and spaced strips 12 with which my improved building blocks 60 or slabs 13 are connected.

In Fig. 3 of the drawing I have shown in detail one of the blocks or slabs 13 which is approximately rectangular in form, and one side wall thereof is provided with a tongue 14 while the other side wall is provided with a groove 15 adapted to receive the tongue 14 of an adjacent block or slab in the construction of a wall. The lower face of the block or slab 13 is provided with a tongue 16 while the upper face thereof is provided with a groove 17 adapted to receive the tongue 16 of the block or slab placed thereon.

Embedded in the block or slab 13 is a rectangular rod-like reinforcing frame 18, which is embedded in the block or slab approximately centrally thereof as is illustrated in Fig. 2 of the drawing, and the side and ends of the frame 18 are connected by a wire mesh or other openwork construction 19, which adds to the reinforcing qualities of the frame 18. The central portion of the frame 18 of the top member 20 thereof is bent downwardly and outwardly through one face of the block or slab 13 as shown at 21 in Fig. 2, and that part of the frame which protrudes through the inner face of the block or slab is bent downwardly into a yoke-shaped spring hook device 22 having a shoulder portion 23, which is adapted to 90 pass beneath the strips 12 of the framework of a building to securely hold and lock the blocks or slabs 13 in position.

It will be apparent that, in the construction of a wall of a building, the blocks or slabs 13 are placed one upon another and one beside the other in which operation the tongues 14—16 pass into the grooves 15—17 respectively in the adjacent blocks or slabs in the manner illustrated in Figs. 1 and 2 of the drawing, and in this operation the yoke-shaped spring hook devices 22 on each of the blocks or slabs is passed over the spaced strips 12 in the manner illustrated in Fig. 2. It will be understood that I am not necessarily limited to the use of one spring hook device 22 on each block as any number of these devices may be employed depending largely on the size of the block or slab and a suitable reinforcement will be provided to 110 suit the size and general structure of the block or slab, and, of course, these blocks or

slabs may be used as facings in which event they will be made comparatively thin and, in other instances, the walls may be constructed of the blocks or slabs 13 only, in which event said blocks or slabs will be made of the usual or required thickness.

In Fig. 5 of the drawing, I have indicated at 24 a part of a roof of a building to the framework 25 of which are secured 10 spaced strips 26. In Fig. 4 of the drawing I have shown a block or slab 28 which is used in the manner of a shingle and composed of comparatively thin cement, concrete or similar substance reinforced by wire 15 mesh, or other openwork material 29 and embedded in the block or slab 28 is a wire frame 30 one side of which is bent to form two yoke-shaped spring hook devices 31 which extend through one face of the 20 block or slab 28, and said frame 30 is also bent to form two spring catch devices 32 which are preferably in line with the spring hook devices 31.

The hook devices 31 are of the same general form and construction as the hook devices 22 shown in Fig. 2 of the drawing, and in the use of the blocks or slabs 28 in constructing the roof of a building, the yoke-shaped spring hook devices 31 are passed 30 over the strips 25 to lock the blocks or slabs in connection therewith, and these blocks or slabs are overlapped in the usual manner and as indicated at 33 in Fig. 5 of the drawing, and the spring catch devices 32 of one 35 slab passes over and engages the upper end portion of the block or slab therebeneath. The first or lower tier of blocks or slabs 28 indicated at 34 in Fig. 5 of the drawing, or the free edges thereof, are reinforced and 40 held in position by a strip 35 secured to the framework 24 of the roof and over which the spring catch devices 32 of the lower tier of blocks or slabs 28 pass.

In the constructions shown in Figs. 1 to 5 45 inclusive, the blocks or slabs are shown square or rectangular in form but, of course, my invention is not limited to this extent as the blocks or slabs may be made of any desired shape or form, and in Fig. 6 I have 50 shown at 36 a V-shaped block or slab for use in corner construction and at 37 in said figure I have shown an arc-shaped block or slab used in the construction of columns, rounded corners, etc.

55 My invention is not necessarily limited to any specific use of the blocks or slabs, or

to that use herein illustrated, nor am I necessarily limited to any specific form of reinforcement in said blocks or slabs, the distinctive feature of the invention being the provision of the spring hook-shaped devices which not only serve to support the blocks or slabs but lock said blocks or slabs against inward, outward or upward movements, as well as serving to aid the supporting of the 60 separate blocks or slabs, and said blocks or slabs may be overlapped or interlocked in any desired manner to form a neat and finished wall or roof construction, and various changes in and modifications of the construction herein shown and described may be made, within the scope of the appended claims, without departing from the spirit of my invention or sacrificing its advantages. 70

Having fully described my invention, what 75 I claim as new and desire to secure by Letters Patent, is:—

1. A block or slab of cementitious material, comprising a rectangular frame embedded in said block or slab, for reinforcing the same, said frame being made of a piece of heavy wire, bent to form a hook-shaped member which projects beyond one side face of the block or slab, the said hook-shaped member being bent outwardly, downwardly, inwardly and again outwardly to engage the upper, inner and under sides of a horizontally disposed support, whereby said block or slab is held and locked to said support. 90

2. A block or slab of cementitious material, comprising a rectangular frame embedded in said block or slab, for reinforcing the same, said frame being made of a piece of heavy wire, bent to form a hook-shaped member which projects beyond one side face of the block or slab, the said hook-shaped member being bent to engage the upper, inner and under sides of a horizontally disposed support, and a spring catch 100 coöperating with said hook-shaped member, the opposite edges of said block or slab being provided respectively with tongue and groove members. 95

In testimony that I claim the foregoing 105 as my invention I have signed my name in presence of the subscribing witnesses this 8th day of March, 1920.

RICHARD MURRAY.
